UNITED STATES PATENT OFFICE

163,710

DINING TABLE STAND

Ruth E. Reid, Selma, Ala.

Application February 2, 1951, Serial No. 14,089

Term of patent 7 years

(Cl. D44—24)

To all whom it may concern:

Be it known that I, Ruth E. Reid, a citizen of the United States of America, residing at Selma, county of Dallas, and State of Alabama, have invented a new, original, and ornamental Design for a Dining Table Stand, of which the following is a specification, reference being had to the accompanying drawing, forming a part thereof wherein:

Figure 1 is an elevational view of a dining table stand, showing my new design.

Figure 2 is another elevational view at right angles to that of Figure 1.

Figure 3 is a top plan view, and

Figure 4 is a sectional view taken on the plane indicated by the line 4—4 of Figure 1.

The present application is a substitute for ap-

plicant's abandoned application for the same invention, filed March 18, 1949, Serial No. D. 1,453.

I claim:

The ornamental design for a dining table stand, as shown.

RUTH E. REID.
